UNITED STATES PATENT OFFICE

133,016

DESIGN FOR A KNIFE SHARPENER

Carlyle C. Wulff, Chicago, Ill.

Application December 17, 1941, Serial No. 104,686

Term of patent 14 years

To all whom it may concern:

Be it known that I, Carlyle C. Wulff, a citizen of the United States, residing at Chicago, in the county of Cook and State of Illinois, have invented a new, original, and ornamental Design for Knife Sharpeners, of which the following is a specification, reference being had to the accompanying drawing, forming part thereof.

Fig. 1 is a front elevational view of a knife sharpener showing my new design;

Fig. 2 is a side elevational view thereof; and

Fig. 3 is a top plan view thereof.

I claim:

The ornamental design for a knife sharpener, as shown.

CARLYLE C. WULFF.
